UNITED STATES PATENT OFFICE.

WILLIAM GRIKSCHET, OF DETROIT, MICHIGAN.

CARBURETOR.

Application filed September 25, 1922. Serial No. 590,472.

The invention relates to carburetors and has for one of its objects the provision of a carburetor having means effected by the suction producing means of the carburetor for drawing liquid fuel thereinto, and also means for preventing the siphoning of the liquid fuel thereinto. Another object is to provide a carburetor provided with an emulsifying chamber discharging into the primary air and with means for automatically varying the supply of liquid fuel and primary air upon variation in the pressure in the carburetor outlet. Other objects of the invention reside in the novel features of construction and combinations and arrangements of parts as more fully hereinafter set forth.

In the drawings:

Figures 1 and 2 are transverse cross sections through the carburetor on the lines 1-1 and 2-2 respectively.

1 is the outlet in the body of the carburetor and 2 the primary air inlet below the outlet and communicating therewith. 3 is a throttle valve in the outlet and 4 is a choke valve within the primary air inlet. 5 is an upwardly extending cylindrical guide through the primary air inlet and spaced from its side walls, and 6 is an auxiliary air tube forming the emulsifying chamber, this air tube being slidable within the guide 5 and having a lower open end communicating with the lateral air passage 7 in the carburetor body, which in turn opens into the vertical air passage 8 in the side wall of the chamber 9. This vertical air passage communicates with the interior of the chamber through the port 10 and the interior of the chamber communicates with the atmosphere through the port 11 located in its side wall diametrically opposite the vertical air passage 8. 12 is a gravity actuated tapering valve having the restricted axial passage 13 therethrough for placing the interior of the chamber 9 into restricted communication with the port 11 at all times. However, as the suction effect within the chamber 9 increases, the valve 12 raises to permit of an increasing flow of air into the chamber. 14 is the liquid fuel tube extending upwardly within the air tube 6 and spaced from its wall to permit of the passage of the auxiliary air. The upper end of this liquid fuel tube terminates within the auxiliary tube and its lower end communicates with the chamber 9 through the lateral fuel passage 15 in the carburetor body. The auxiliary air tube 6 is provided with the longitudinally spaced ports 16 for placing its interior in communication with the outlet 1, the upper port being at all times in communication with the outlet.

17 is a vertically reciprocable plunger within the cylinder 18 formed in the carburetor body, this plunger variably restricting the communication between the primary air inlet and the outlet and its position being determined by the pressure within the outlet in rear of the throttle valve. The vertical position of the plunger is dependent upon the difference in the pressures below and above the plunger, the pressure therebelow being the same as the pressure in the primary air inlet while the pressure thereabove is the same as the pressure in the outlet in rear of the throttle valve, this being secured by placing the interior of the cylinder above the plunger in communication with the outlet in rear of the throttle valve through the restricted equalizing passage 19. The lowermost position of the plunger is determined by means of the coil spring 20 surrounding the guide rod 21 which extends into the plunger. 22 is a metering pin secured to the plunger and cooperating with the liquid fuel tube 14 to variably restrict the flow of the liquid fuel therethrough into the emulsifying chamber formed by the air tube 6. The air tube is also secured to the plunger, the arrangement being such that as the plunger rises, the primary air passing through the air inlet 2 into the outlet 1 increases, the liquid fuel passing through the liquid fuel tube 14 increases, and the mixture of this liquid fuel and the auxiliary air passing through the air tube 6 and entering the outlet 1 increases.

The vertical position of the liquid fuel tube 14 relative to the metering pin 22 is manually adjustable through the lever 23 engaging the lower end of the liquid fuel tube and mounted upon the rock shaft 24 to which is connected the lever 25 operable from the dash of the motor vehicle by the flexible connection 26. A coil spring 27 yieldably holds the liquid fuel tube in its uppermost position.

As shown in the present instance, liquid fuel is drawn into the carburetor from the supply tank 28 by the suction producing means of the carburetor such as an internal combustion engine, and the chamber 9 forms

part of the discharge connection between the tank and the carburetor. The suction for drawing the liquid fuel from the tank is secured through the port 10 connecting the interior of the chamber 9 near its upper end with the vertical air passage 8 in the side wall of the chamber which in turn connects into the lateral air passage 7 leading to the air tube 6. To prevent siphoning of the liquid fuel when the motor vehicle is doing down hill, I have provided the float 29 in the chamber 9 to which is secured the valve 30 for closing the port 31 into the chamber. The liquid fuel entering the chamber 9 may discharge through the liquid fuel tube 14 owing to the differential pressures at the surface of the liquid fuel in the chamber and at the discharge end of the liquid fuel tube. Consequently, liquid fuel may be entering and discharging from the chamber at the same time. However, if for any reason, siphoning of the liquid

fuel should occur so that it enters the chamber faster than it discharges, the float within the chamber actuates the valve to close 25 the same and prevent further siphoning.

What I claim as my invention is:

In a carburetor, the combination with the body having an air inlet and an outlet, of a cylinder, a plunger slidable within said cylinder for controlling the communication of said air inlet with said outlet, an air tube depending from said plunger and adapted to variably communicate with said outlet upon movement of said plunger, a liquid fuel tube extending upwardly within said air tube and spaced therefrom, a metering pin secured to said plunger and cooperating with said liquid fuel tube to variably control the flow of liquid fuel therethrough, and means for placing the interior of said cylinder in communication with said outlet.

In testimony whereof I affix my signature.

WILLIAM GRIKSCHET.
